UNITED STATES PATENT OFFICE.

WILLIAM LAWRENCE BALLS AND FREDERICK HUTCHINS, OF MANCHESTER, ENGLAND, ASSIGNORS TO THE FINE COTTON SPINNERS' AND DOUBLERS' ASSOCIATION LIMITED, OF MANCHESTER, ENGLAND, A BRITISH COMPANY.

PREPARATION OF FIBROUS MATERIALS FOR SPINNING.

Application filed February 23, 1924. Serial No. 694,543.

To all whom it may concern:

Be it known that we, WILLIAM LAWRENCE BALLS and FREDERICK HUTCHINS, both subjects of the King of England, both residing at Manchester, Lancashire, England, have invented certain new and useful Improvements in the Preparation of Fibrous Materials for Spinning, of which the following is a specification.

10 This invention is for improvements in or relating to the preparation of fibrous materials for spinning, and is applicable for use with cotton and various other fibres.

Commonly in preparing fibrous material 15 for spinning, the sliver delivered from the draw-frame hereinafter termed "finished draw-frame or like sliver," is passed through several other drafting machines before it reaches the mule or other spinning machine.

20 Usually the sliver is passed through various flyer frames in order to be thus drafted, namely through some or all of slubbing, intermediate, roving, and jack frames, each of which further drafts and partly twists 25 the sliver. It is an object of the present invention to reduce materially the number of these drafting operations. This is desirable, not merely with a view to reducing the number of machines necessary in an in-

20 stallation, but also because of the character of the sliver produced, since it is found in practice that the larger the number of drafting operations to which the sliver is subjected, the larger the number of faults and 35 irregularities it is liable to develop. What is required is a draft of somewhere in the neighbourhood of 200, and to secure efficient results with such a high draft, the feed of the sliver to the drafting device,

40 though relatively extremely slow, must be very accurate and regular. It will be understood that the term "drafting device" is employed herein to denote the delivery rollers or the equivalent which receive the 45 sliver from the feeding and restraining device and between which and the feeding and restraining device the draft occurs.

According to one feature of the present invention there is provided a machine for 50 drafting fibrous materials comprising a drafting device (such as a set of constantly

rotating drafting rollers), a feeding and restraining device (such as another set of rollers) co-operating therewith, and sliver guide plates (such as co-operating upper 55 and lower plates) lying between the drafting and the feeding and restraining devices and bearing on substantially the whole length of sliver between the two said devices, which machine is characterized in that 60 the pressure of the guide plates upon the sliver is automatically intermittently relieved (for example by lifting an upper plate) during the operation of the machine. Such a machine is suitable for use for 65 either ordinary drafts or for the high drafts just referred to and it will be found that by having the guide plates bearing upon substantially the whole length of the sliver between the two sets of rollers or other 70 device the plate will keep it evenly compressed. When the pressure is relieved, the drafting device will be able to feed the portion of the fibrous material forward, but since the pressure is only relieved inter- 75 mittently the rate of feed can be made extremely slow and the desired accurate results thus obtained. The feeding motion of the sliver through the plates is assisted by pulling upon it from the front, thus tending 80 to keep the individual fibres straight and taut.

In a machine constructed in accordance with the aforesaid feature of the present invention, the feeding and restraining device 85 may be constantly driven, but according to another feature of the invention means are provided for intermittently operating (for example intermittently rotating) the feeding and restraining device during the 90 drafting operation of the machine. This intermittent operation may take the form of driving it at a constant speed but imparting to it an intermittent reciprocation bodily 95 towards and from the drafting device; or it may take the form of imparting an intermittent rotation or like operative motion to the feeding and restraining device, without any such bodily reciprocation; or the 100 intermittent rotation or like operative motion may be superimposed upon the said intermittent reciprocation. The choice be-

tween these various alternatives will depend upon the type of machine required, or the circumstances in which it is to be used, or the nature of the fibrous material with which 5 it is required to deal. They will all be found, however, to be suitable for the regular but relatively extremely slow feed of the sliver to the high speed drafting device.

The relief of the pressure of the guide 10 plates on the sliver is preferably timed to coincide with the operation of the feeding and restraining device so as to secure a proper feed of the material to the drafting device. Furthermore, during the drafting 15 operation of the machine, the sliver guide plates may be intermittently reciprocated bodily towards and from the drafting device, this reciprocation being preferably synchronous with that of the feeding and re- 20 straining device. Moreover, it will be found advantageous to time the relief of the pressure of the guide plates on the sliver to coincide with the concluding portion of the translatory movement of such plates towards 25 the drafting device. For effecting this the reciprocating movement of the sliver guide plates may be arranged to cause them to encounter a separating cam towards the end of their movement in the direction of the 30 drafting device. Thus the pressure upon the sliver may be relieved at the instant when the drafting rollers take hold of the front ends of the fibres.

For imparting the aforesaid intermittent 35 rotation to the feeding and restraining device, many types of mechanism are suitable, such as toothed or frictional ratchet gear, escapement mechanism or Maltese cross gear. In one convenient construction which con- 40 stitutes a feature of the invention, the feeding and restraining device is operated by a toothed wheel engaged and driven by a disc whereof one portion of the periphery lies in one plane and another portion of the periph- 45 ery extends in the form of a tongue having a free end which lies in another plane separated from the first plane by a distance corresponding to the pitch of the teeth of the said wheel. Thus as the disc is rotated, so long as the first named portion of the periph- 50 ery is engaging the wheel no rotation will be imparted to the latter, but as soon as the tongue enters between the teeth of the wheel, the slope of the tongue will cause the wheel 55 to revolve a portion of a turn. The extent of movement imparted by the tongue to the wheel will be such that as the tongue leaves the wheel there will be a space between two adjacent teeth in position for the other part 60 of the periphery of the disc to enter as it continues its rotation. In this way a step-by-step rotation will be imparted to the wheel, and according to the slope of the tongue so the speed at which the actual 65 partial rotation takes place may be varied.

When, as indicated above, the feeding and restraining device is intermittently reciprocated bodily towards and from the drafting device, the drive (for example rotation) is preferably imparted to it by a two-part rotary shaft whereof the parts are connected together endwise by a flexible coupling, and the one shaft part moves with the feeding and restraining device in its reciprocatory movement, and the other shaft part does not partake of such reciprocatory movement but transmits driving rotation to the first named shaft part.

The provision of means for automatically intermittently relieving the pressure of the 80 guide plates upon the sliver is not essential to all constructions of machines according to the present invention since it is believed to be novel to construct a machine for drafting fibrous materials which comprises in 85 combination a drafting device (such as a set of constantly rotating drafting rollers), a feeding and restraining device (such as another set of rollers) co-operating therewith, sliver guide plates (such as cooperating upper and lower plates) lying between the drafting and the feeding and restraining devices and bearing on substantially the whole length of sliver between 90 the two said devices, means for intermittently operating (for example intermittently rotating) the feeding and restraining device during the drafting operation of the machine 95 and means whereby, during the drafting operation of the machine, the feeding and 100 restraining device is intermittently reciprocated bodily towards and from the drafting device, whether or not the sliver guide plates are also similarly intermittently reciprocated bodily. This combination of parts, there- 105 fore, constitutes one of the features of the present invention as applied to all types of draft.

According to a further feature of the invention sliver-condensing means are provided for operating upon the sliver after it has issued from the drafting device. The delivery from the drafting device, particularly when the aforesaid high draft is being applied, is of ribbon formation. The sliver-condensing device will render this ribbon suitable for immediate use in a mule or other spinning machine as desired and will provide for proper spinning of the inner and outer fibres. The sliver-condensing device 115 may take the form of a pair of rollers set at right angles to the rollers of the drafting device and having a surface speed the same as or slightly in excess of the surface speed 120 of the drafting rollers.

Another combination of parts which is believed to be novel, and which constitutes a feature of the invention, comprises a drafting device (such as a set of constantly rotating drafting rollers), a feeding and re- 125

straining device (such as another set of rollers) cooperating therewith, mechanism whereby the speed of operation upon the material being drafted of the two said devices is so correlated that, without any other drafting means being interposed between the two said devices, so high a draft (for example of 200) is imparted to the said material that if a "finished draw-frame or like sliver" is fed to the feeding and restraining device and passes from this device to the drafting device, the latter delivers a sliver suitable, without further drafting in flyer frames or the like, for immediate spinning, say by a mule, and sliver-condensing means operating upon the sliver after it has issued from the drafting device. The speed correlation may be obtained in various ways. For instance the two sets of rollers or other devices may each be driven at a constant speed the one from the other by suitable accurate gearing, the speed of the drafting device being, of course, very much greater than the speed of the feeding and restraining device. Or the draft of the feeding and restraining device may be intermittent, as already described, and the aforesaid reciprocatory movement of the feeding and restraining device may or may not be adopted according to circumstances.

For a more complete understanding of these and other features of the invention there will now be described, by way of example only and with reference to the accompanying drawings, certain constructional forms of part of a drafting machine according to the invention. It is to be understood, however, that the invention is not limited to the precise constructional details set forth.

40 In these drawings:—

Figure 1 is a sectional elevation on the line 1—1 of Figure 2.

Figure 2 is a sectional elevation on the line 2—2 of Figure 1.

45 Figure 3 is a sectional view corresponding to a portion of Figure 1 but showing the parts in a different position.

Figure 4 is a detail section on the line 4—4 of Figure 1 showing the sliver-condensing means.

Figure 5 is a detail plan view of the driving mechanism for the feeding and restraining rollers.

50 Figure 6 is a partial elevation of the parts shown in Figure 5.

Figure 7 is a detail view, on a scale larger than that of the preceding figures, of a modified construction of the sliver guide plates, and

55 Figure 8 is a similar view of another modified construction.

Like reference numerals indicate like parts throughout the drawings.

60 A pair of drafting rollers are shown in end elevation in Figure 1 at 10 and 11, and

one or both of these rollers may be driven through the respective shafts 12 and 13, or in some other convenient way. The rollers are supported in a stationary bracket 14, and a co-operating pair of feeding and restraining rollers are shown at 15 and 16, they being supported in frame members 17 which are pivoted to rock about a spindle 18. The rollers 10, 11, 15 and 16 may be of any desired length and if thought necessary one or more intermediate frame members such as 17 may be employed along the length of the rollers.

The frame members 17 are tied together by rods 21 and 22 and the latter carries a roller 23 which engages the edge of a rotary cam 24. By means of this cam 24 the frame is rocked about the pivot 18 thereby moving the rollers 15 and 16 towards and from the rollers 10 and 11.

Carried by the frame member 17 is a rod 25 with a pair of blocks 26 and 27 on it. These blocks may be adjustable along the rod 25 and the latter may also be adjustable in the frame member 17 if so desired. The block 26 pivotally carries one end of a lower sliver guide plate 28 and the block 27 pivotally carries a bar 29 which is pivoted to one end of an upper sliver guide plate 30. The bar 29 is drawn towards the rod 25 by a spring 31 and it will be understood that the other ends of the plates 28 and 30 may be correspondingly supported. Likewise there may be similar intermediate supports if so desired. The sliver lying between the plates 28 and 30 will be subject to pressure consequent upon the weight of the upper plate 30 and this pressure will be supplemented by the pressure exerted by the springs 31.

It will be understood that the sliver guide plates 28 and 30 rock to and fro with the frame members 17. To relieve the pressure of the plates upon the sliver, the bracket 14 is provided with a separating cam 32 whereof the operating surface will be encountered by a part moving with the upper plate when the latter is towards the end of its movement in the direction of the rollers 10 and 11. The effect of the cam 32 will be to raise the upper guide plate as indicated in Figure 1. This figure shows the parts in the position they occupy when the rollers 15 and 16 are nearest the rollers 10 and 11, while Figure 3 shows the position when the rollers are most widely separated.

The weight of the upper guide plate 30 may be amplified by other weights applied to it if desired and, as already indicated, it is desirable to employ plates which are sufficiently large to reach as far as practical towards the gripping points of the two pairs of rollers 10 and 11, and 15 and 16 between which they are situated; particularly is it desirable that the plates should lie

as close as possible to the rollers 10 and 11. In choosing the dimensions of the plates, of course, provision must be made for the reciprocatory motion which is to be imparted to them, but the amplitude of this motion will not usually exceed half an inch.

As already stated the drive of the rollers 15 and 16 may be either constant or intermittent. A suitable mechanism for securing 10 an intermittent drive is shown in the drawings. The shaft 33 of the roller 16 is prolonged, as shown in Figure 2, and provided with a bevel wheel 34 which engages another wheel 35 upon a driving shaft. This 15 shaft is in two parts 36 and 37 whereof the former is received in bearings in a prolongation 38 of the rod 21 and a square rod 39, carried by the frame member 17. The outer ends of the parts 38 and 39 are joined by an 20 arm 40. It follows from this construction that the part 36 of the driving shaft will partake of the rocking movement of the frame member 17 about the pivot 18. The part 37 of the driving shaft is supported 25 in suitable stationary bearings, not shown, and is connected to the part 36 by a suitable flexible coupling composed for example of two metal discs 41 and 42 and an intermediate leather disc 43. Thus drive may be 30 transmitted from the part 37 to the part 36 even though the latter rocks with the frame member 17 and the former does not.

The part 37 of the driving shaft carries a disc 44 which is slotted at 45 to form teeth, 35 the slots being slightly oblique as will be clear from an inspection of Figure 6 of the drawings. Mounted in position to engage with the slots 45 is a disc 46 carried upon a suitable main driving shaft 47 which may 40 also be the shaft upon which the cam 24 aforesaid is mounted. In this way synchronism will be established between the intermittent drive of the rollers 15 and 16 and their rocking movement. A portion of the 45 periphery of the disc 46 is cut and bent to form a tongue 48, the distance between the end of the tongue and the remainder of the disc being equal to the distance between the slots 45 of the wheel 44. Thus, during the 50 major portion of the rotation of the disc 46 no rotation will be imparted to the wheel 44, but when the root of the tongue 48 encounters the wheel 44 rotation of the latter will commence and will be continued until the 55 wheel has been moved a sufficient amount to permit the unbent portion of the periphery of the disc 46 to enter the succeeding slot in the wheel as the rotation of the disc proceeds. In this way an intermittent feed 60 will be imparted to the roller 16, and the speed at which this roller will move would be governed by the slope of the tongue 48 between its root and its free end.

After the sliver leaves the rollers 10 and 65 11 it encounters the sliver-condensing device

which in the construction illustrated consists of a pair of vertical rollers 49 and 50, the former of which is shown as being driven through bevel gearing. The roller 50 may be frictionally or otherwise driven 70 from its fellow and more than one pair of these co-operating condensing rollers may be provided if desired, the arrangement preferably being such that the sliver is permitted to proceed onwards in a more or less 75 straight line.

Instead of using sliver guide plates of metal throughout as shown at 28 and 30, facing strips 51 and 52 (Figure 7) of leather or other material having a higher coefficient 80 of friction than metal may be employed. Alternately, one or both of the plates may have corrugated faces as at 53 and 54, Figure 8, the length of the corrugations being at right angles to the direction of travel 85 of the sliver. When both plates are corrugated, the projections on the one should preferably lie opposite the depressions in the surface of the other, while to set a limit to the closeness with which the plates may 90 approach each other, stops, such as 55, preferably adjustable, may be fitted to the plates, whether or not they are corrugated.

From the foregoing it will be appreciated that the present invention provides for the 95 removal of one of the chief sources of irregularity in finished yarn, namely the subjecting of the sliver to a plurality of drafting operations. This irregularity is produced in drafting by irregular displacement 100 of the individual fibres, the fibres which should move forward, dragging with them prematurely other fibres the forward ends of which lie further back in the sliver. To overcome this premature displacement of 105 the fibres it is necessary to rely upon the mutual support afforded by the fibres and this mutual support can be safely increased within limits by the employment of the sliver guide plates described above. These 110 plates also overcome the natural tendency of the sliver to expand due to the resilience of the fibres and thus maintain the sliver under that degree of control which is requisite in view of the extreme accuracy of 115 feed essential in order to deal with the high draft which is contemplated according to the present invention. This high draft in itself also tends to produce regularity since only a very small percentage of the fibres 120 in the sliver have to be moved forward at a time.

The improved results which are obtained according to the invention are not only due to the fact that only a single drafting device, with a co-operating feeding and restraining device is employed, so that the whole draft is effected in one operation, but are also due to the fact that "finished draw-frame or like sliver" can be fed to the feed- 125 130

ing and restraining device. In such sliver the fibres lie straighter and more parallel, and more regularly spaced than they do in any sliver or roving produced by the machines which it is the present custom to employ to impart a draft to the sliver after it has left the draw-frame. Furthermore, since the sliver is drawn through the guide plates by pulling upon it from the front, the fibres are kept taut and straight, and the feeding and restraining device is arranged to operate merely to release sliver regularly according to the pull exerted upon it by the drafting device as the latter grips certain of the fibres in the sliver. Considering an individual fibre, the pull thus exerted is at its maximum when the fibre is starting to move and diminishes rapidly when once the movement has commenced and it is with this in view that the intermittent operation of the feeding and restraining device is employed since the feed of the sliver to the drafting device can be arranged to cease, and the bulk of the sliver can actually be withdrawn therefrom, as soon as the proper number of fibres have been gripped by the drafting device and extracted from the sliver.

It is to be understood that the drafted material prepared according to the present invention can be fed to any desired form of spinning mechanism, not necessarily to a mule, and that while it is particularly advantageous to supply a finished draw-frame or like sliver to the feeding and restraining device of the present invention for the purpose of converting the said sliver directly into yarn, other forms of the fibrous material could be dealt with for preparatory purposes; for example, a lap, such as is used for feeding a cotton combing machine or is formed in other machines, may be manipulated by the same mechanism. By the phrase "preparatory purposes" it is therefore intended to embrace any operation in which a high draft, as hereinbefore contemplated, is obtained, whether or not the sliver or the like made is fed without further manipulation or preparation to a spinning machine. For instance the invention could be applied to a cotton or like grading or sorting machine.

It is also to be understood that the invention is not limited to the precise constructional details hereinbefore set forth. For example, for a drafting machine as ordinarily understood, the reciprocatory movement of the feeding and restraining rollers and of the sliver guide plates need not be employed, the pressure of the latter upon the sliver being relieved by suitable automatic means alternative to those illustrated in the drawings.

We claim:

1. A machine for drafting fibrous ma-

terials, comprising a drafting device, an intermittently actuated feeding and restraining device co-operating therewith, sliver guide plates lying between the drafting and the feeding and restraining devices and bearing on substantially the whole length of sliver between the two said devices, and means for automatically intermittently relieving the pressure of the guide plates on the sliver during the drafting operation of the machine.

2. A machine for drafting fibrous materials, comprising a drafting device, an intermittently actuated feeding and restraining device co-operating therewith, upper and lower sliver guide plates lying between the drafting and the feeding and restraining devices and bearing on substantially the whole length of sliver between the two said devices, and means for automatically intermittently lifting the upper plate to relieve the pressure of the guide plates upon the sliver during the drafting operation of the machine.

3. A machine for drafting fibrous materials, comprising a set of constantly rotating drafting rollers, a set of intermittently actuated feeding and restraining rollers co-operating therewith, opposed sliver guide plates lying between the drafting and the feeding and restraining devices and bearing on substantially the whole length of sliver between the two said devices, and automatic means for intermittently moving one of said plates away from the sliver to relieve the pressure of the plates upon the sliver during the drafting operation of the machine.

4. A machine for drafting fibrous materials, comprising a drafting device, an intermittently actuated feeding and restraining device co-operating therewith, sliver guide plates lying between the drafting and the feeding and restraining devices, friction facing strips on said plates bearing on substantially the whole length of sliver between the drafting and the feeding and restraining devices, and means for automatically intermittently relieving the pressure of the guide plates upon the sliver during the drafting operation of the machine.

5. A machine for drafting fibrous materials, comprising a drafting device, an intermittently actuated feeding and restraining device co-operating therewith, sliver guide plates lying between the drafting and the feeding and restraining devices, corrugated friction facing strips on said plates bearing on substantially the whole length of sliver between the drafting and the feeding and restraining devices, and means for automatically intermittently relieving the pressure of the guide plates upon the sliver during the drafting operation of the machine.

6. A machine for drafting fibrous materials, comprising a drafting device, an intermittently actuated feeding and restraining device co-operating therewith, sliver 5 guide plates lying between the drafting and the feeding and restraining devices, friction facing strips on said plates, which strips are corrugated transversely of the direction of travel of the sliver between the plates, 10 said strips bearing on substantially the whole length of sliver between the drafting and the feeding and restraining devices, and means for automatically intermittently relieving the pressure of the guide plates 15 upon the sliver during the drafting operation of the machine.

7. A machine for drafting fibrous materials comprising a drafting device, an intermittently actuated feeding and restraining 20 device co-operating therewith, sliver guide plates lying between the drafting and the feeding and restraining devices and bearing on substantially the whole length of sliver between the two said devices, 25 means for automatically intermittently relieving the pressure of the guide plates upon the sliver during the drafting operation of the machine, and means for intermittently operating the feeding and restraining device 30 during the drafting operation of the machine.

8. A machine for drafting fibrous materials, comprising a set of constantly rotating drafting rollers, a set of rotary 35 feeding and restraining rollers co-operating therewith, sliver guide plates lying between the drafting and the feeding and restraining devices and bearing on substantially the whole length of sliver between the two 40 said devices, means whereby the pressure of the guide plates upon the sliver is automatically intermittently relieved during the drafting operation of the machine, and means for intermittently rotating the feeding and restraining rollers during the drafting 45 operation of the machine.

9. A machine for drafting fibrous materials comprising a drafting device, a feeding and restraining device co-operating 50 therewith, sliver guide plates lying between the drafting and the feeding and restraining devices and bearing on substantially the whole length of sliver between the two said devices, means whereby the pressure of the 55 guide plates upon the sliver is automatically intermittently relieved during the drafting operation of the machine, and means for intermittently operating the feeding and restraining device at times coincident with the 60 relief of the pressure upon the guide plates on the sliver.

10. A machine for drafting fibrous materials comprising a drafting device, a feeding and restraining device co-operating 65 therewith, sliver guide plates lying between

the drafting and the feeding and restraining devices and bearing on substantially the whole length of sliver between the two said devices, means whereby the pressure of the guide plates upon the sliver is automatically 70 intermittently relieved during the drafting operation of the machine, and means for intermittently reciprocating the feeding and restraining device bodily towards and from the drafting device during the drafting 75 operation of the machine.

11. A machine for drafting fibrous materials, comprising a set of constantly rotating drafting rollers, a set of rotary feeding and restraining rollers co-operating therewith, sliver guide plates lying between the drafting and the feeding and restraining devices and bearing on substantially the whole length of sliver between the two said devices, means whereby the pressure of the 80 guide plates upon the sliver is automatically intermittently relieved during the drafting operation of the machine, means for intermittently rotating the feeding and restraining rollers during the drafting operation of 85 the machine and means for intermittently reciprocating said last-named rollers bodily towards and from the drafting rollers.

12. A machine for drafting fibrous materials, comprising a drafting device, a feeding and restraining device co-operating 90 therewith, sliver guide plates lying between the drafting and the feeding and restraining devices and bearing on substantially the whole length of sliver between the two 95 said devices, means whereby the pressure of the guide plates upon the sliver is intermittently relieved during the drafting operation of the machine, and means for intermittently reciprocating the sliver guide 100 plates bodily towards and from the drafting device during the drafting operation of the machine.

13. A machine for drafting fibrous materials comprising a drafting device, a feeding and restraining device co-operating 105 therewith, sliver guide plates lying between the drafting and the feeding and restraining devices and bearing on substantially the whole length of sliver between the two said 110 devices, means whereby the pressure of the guide plates upon the sliver is automatically intermittently relieved during the drafting operation of the machine, and means for intermittently reciprocating the sliver guide 115 plates and the feeding and restraining device bodily and synchronously towards and from the drafting device during the drafting 120 operation of the machine.

14. A machine for drafting fibrous materials comprising a drafting device, a feeding and restraining device co-operating 125 therewith, sliver guide plates lying between the drafting and the feeding and restraining devices and bearing on substantially the 130

whole length of sliver between the two said devices, means whereby the pressure of the guide plates upon the sliver is automatically intermittently relieved during the drafting 5 operation of the machine, a rocking frame supporting the sliver guide plates and the feeding and restraining device, and means for rocking said frame to move the sliver guide plates and the feeding and restraining 10 device intermittently bodily towards and from the drafting device.

15. A machine for drafting fibrous materials comprising a drafting device, a feeding and restraining device co-operating therewith, sliver guide plates lying between the drafting and the feeding and restraining devices and bearing on substantially the whole length of sliver between the two said devices, means for intermittently reciprocating 20 the sliver guide plates bodily towards and from the drafting device during the drafting operation of the machine, and means whereby the pressure of the guide plates upon the sliver is automatically intermittently relieved, the timing being such that the relief of the pressure of the guide plates on the sliver coincides with the concluding portion of the translatory movement of such plates towards the drafting 25 device.

16. A machine for drafting fibrous materials comprising a drafting device, a feeding and restraining device co-operating therewith, opposed sliver guide plates lying 30 between the drafting and the feeding and restraining devices and receiving between them and bearing upon substantially the whole length of sliver between the said drafting and the feeding and restraining 35 devices, means for intermittently reciprocating the said guide plates bodily towards and from the drafting device during the drafting operation of the machine, and a cam supported in the line of movement of the guide plates so as to be encountered by the latter towards the end of their movement in the direction of the drafting device and cause said plates to separate, for the 40 purpose specified.

50. 17. A machine for drafting fibrous materials comprising a drafting device, a feeding and restraining device co-operating therewith, sliver guide plates lying between the drafting and the feeding and restraining devices and bearing on substantially the whole length of sliver between the two said devices, means whereby the pressure of the guide plates upon the sliver is automatically intermittently relieved during the drafting 55 operation of the machine, and means for intermittently operating the feeding and restraining device during the drafting operation of the machine, said last-named means comprising a toothed wheel and a disc which engages and drives said 60

wheel, one portion of the periphery of the disc lying in one plane and another portion of the periphery extending in the form of a tongue having a free end which lies in another plane separated from the first said 70 plane by a distance corresponding to the pitch of the teeth of the said wheel, for the purpose specified.

18. A machine for drafting fibrous materials comprising a drafting device, a feeding and restraining device co-operating therewith, sliver guide plates lying between the drafting and the feeding and restraining devices and bearing on substantially the whole length of sliver between the two said devices, means whereby the pressure of the guide plates upon the sliver is automatically intermittently relieved during the drafting operation of the machine, means whereby the feeding and restraining device 80 is intermittently reciprocated bodily towards and from the drafting device during the drafting operation of the machine, and means for intermittently driving the feeding and restraining device during the drafting 85 operation of the machine, said last-named means comprising a two-part rotary shaft and a flexible coupling which connects the two parts of the shaft together endwise, the one shaft part moving with the feeding and restraining device in its reciprocatory movement, and the other shaft part not partaking of such reciprocatory movement but transmitting driving rotation to the first-named shaft part. 90

19. A machine for drafting fibrous materials, comprising in combination a drafting device, a feeding and restraining device co-operating therewith, sliver guide plates lying between the drafting and the feeding and restraining devices and bearing on substantially the whole length of sliver between the two said devices, means for intermittently operating the feeding and restraining device during the drafting operation of the machine, and means whereby, during the drafting operation of the machine, the feeding and restraining device is intermittently reciprocated bodily towards and from the drafting device. 105

20. A machine for drafting fibrous materials, comprising in combination a drafting device, a feeding and restraining device co-operating therewith, sliver guide plates lying between the drafting and the feeding and restraining devices and bearing on substantially the whole length of sliver between the two said devices, means for intermittently operating the feeding and restraining device during the drafting operation of the machine, means whereby, during the drafting operation of the machine, the feeding and restraining device is intermittently reciprocated bodily towards and from the drafting device, and means where- 110 115 120 125 130

by the sliver guide plates are also similarly intermittently reciprocated bodily.

21. A machine for drafting fibrous materials, comprising in combination a set of 5 constantly rotating drafting rollers, a set of feeding and restraining rollers co-operating therewith, co-operating upper and lower sliver guide plates lying between the drafting and the feeding and restraining rollers 10 and bearing on substantially the whole length of sliver between the two said sets of rollers, means for intermittently rotating the feeding and restraining rollers during the drafting operation of the machine, 15 and means whereby, during the drafting operation of the machine, the feeding and restraining rollers are intermittently reciprocated bodily towards and from the drafting rollers.

22. A machine for drafting fibrous materials, comprising in combination a drafting device, a feeding and restraining device co-operating therewith, sliver guide plates lying between the drafting and the 25 feeding and restraining devices and bearing on substantially the whole length of sliver between the two said devices, means for intermittently operating the feeding and restraining device during the drafting operation 30 of the machine, means whereby, during the drafting operation of the machine, the feeding and restraining device is intermittently reciprocated bodily towards and from the drafting device, and sliver-condensing 35 means operating upon the sliver after it has issued from the drafting device.

23. A machine for drafting fibrous materials comprising a drafting device, a feeding and restraining device co-operating therewith, sliver guide plates lying between the 40 drafting and the feeding and restraining devices and bearing on substantially the whole length of sliver between the two said devices, means whereby the pressure of the 45 guide plates upon the sliver is automatically intermittently relieved during the drafting operation of the machine, and sliver-condensing means operating upon the sliver after it has issued from the drafting device.

24. A machine for drafting fibrous materials, comprising in combination a set of 50 constantly rotating drafting rollers, a feeding and restraining device co-operating therewith, means for intermittently feeding 55 a sliver to said drafting rollers, and sliver-condensing rollers operating upon the sliver after it has issued from the drafting rollers, the axes of rotation of which sliver-condensing rollers nearest the drafting rollers are 60 fixed to lie transversely of the axes of the adjacent drafting rollers, for the purpose specified.

25. A machine for drafting fibrous materials comprising a drafting device, a feeding and restraining device co-operating 65

therewith, sliver guide plates lying between the drafting and the feeding and restraining devices and bearing on substantially the whole length of sliver between the two said devices, said guide plates forming a corrugated surface to guide the sliver, means for intermittently operating the feeding and restraining device during the drafting operation of the machine, and means whereby, during the drafting operation of the machine, the feeding and restraining device is intermittently reciprocated bodily towards and from the drafting device. 70 75

26. A machine for drafting fibrous materials comprising a drafting device, a feeding and restraining device co-operating therewith, sliver guide plates lying between the drafting and the feeding and restraining devices and bearing on substantially the 80 whole length of sliver between the two said devices, stops provided on said guide plates to regulate the closeness with which the plates may approach each other, and means whereby the pressure of the plates upon the sliver is automatically intermittently relieved during the drafting operation of the machine. 85 90

27. A machine for drafting fibrous materials, comprising in combination a set of 95 constantly rotating drafting rollers, an intermittently actuated feeding and restraining device co-operating therewith, means for intermittently feeding a sliver to said drafting rollers, and sliver-condensing rollers arranged to operate upon the sliver after it 100 has issued from the drafting rollers, the axes of rotation of which sliver-condensing rollers are fixed to lie transversely of the axes of the adjacent drafting rollers, substantially as described. 105

28. A machine for drafting fibrous materials, comprising in combination a set of 110 constantly rotating drafting rollers, a feeding and restraining device cooperating therewith, means comprising opposed sliver guide plates for intermittently feeding a sliver to said drafting rollers, and sliver-condensing rollers arranged to operate upon the sliver after it has issued from the drafting rollers, the axes of rotation of which sliver-condensing rollers are fixed to lie transversely of the axes of rotation of the adjacent drafting rollers, substantially as described. 115

29. A machine for drafting fibrous materials, comprising in combination a set of 120 constantly rotating drafting rollers, an intermittently actuated feeding and restraining device cooperating therewith, opposed sliver guide plates lying between the drafting and the feeding and restraining devices 125 and bearing on substantially the whole length of sliver between the two said devices, automatic means for intermittently moving one of said plates away from the sliver to relieve the pressure of the plates upon the 130

sliver during the drafting operation of the machine, and sliver-condensing rollers arranged to operate upon the sliver after it has issued from the drafting rollers, the 5 axes of rotation of which sliver-condensing rollers nearest the drafting rollers are fixed to lie transversely of the axes of the adja-

cent drafting rollers, substantially as described.

In testimony whereof we have signed our 10 names to this specification.

WILLIAM LAWRENCE BALLS.
FREDERICK HUTCHINS.
